(57) **CLAIM**

The ornamental design for a cartridge or foil holder for a one and two component dispenser, as shown and described.

DESCRIPTION

FIG. 1 is an upper front-right perspective view of a cartridge or foil holder for a one and two component dispenser illustrating our ornamental design;

FIG. 2 is an upper front-left perspective view thereof;

FIG. 3 is a lower rear-left perspective view thereof;

FIG. 4 is a lower rear-right perspective view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a top plan view thereof;

FIG. 10 is a bottom plan view thereof;

FIG. 11 is an upper front-right perspective view thereof, illustrating an open front plate;

FIG. 12 is a front elevation view thereof, illustrating the open front plate of FIG. 11; and,

FIG. 13 is a side elevation partial section view of FIG. 9 along section lines 9-9.

The broken line showing of the dispenser body is provided for purposes of environment and forms no part of the claimed design.

1 Claim, 13 Drawing Sheets
